RAYMOND P. PACKARD, OF TACOMA, WASHINGTON.

CONTROLLING MECHANISM.

1,231,055.

Specification of Letters Patent. Patented June 26, 1917.

Application filed January 18, 1917. Serial No. 143,197.

To all whom it may concern:

Be it known that I, RAYMOND P. PACKARD, a citizen of the United States, residing at Tacoma, in the county of Pierce, State 5 of Washington, have invented certain new and useful Improvements in Controlling Mechanism, of which the following is a specification.

This invention relates to devices for pulling or pushing a controlling wire by the rotary motion of a controlling handle, and has special reference to the control of the engine in a motor-cycle and other similar uses. The invention is especially adapted 10 for the operation of the motor cycle control wire which is mounted within a coiled spring casing and which has longitudinal motion alone therein. The objects of the invention are to provide means whereby said 15 wire is given its longitudinal motion therein when a rotary motion is given to the hand-grip, said mechanism being self-contained and readily inserted in or removed from the handle bar in which it is mounted, and 20 which is simple to make, assemble and install, and is effective in its action.

I attain these and other objects by the devices, mechanisms, and arrangements illustrated in the accompanying drawings, in 25 which—

Figure 1 is a longitudinal section of my device in use; Fig. 2 is an enlarged cross-section thereof; Fig. 3 is a side elevation of the rotary sleeve; Fig. 4 is a similar view 30 of the fixed sleeve; and Figs. 5 and 6 are elevations respectively of the conical screw plug for expanding one end of the fixed sleeve and the conical screw nut for contracting the other end thereof.

Similar numerals of reference refer to 40 similar parts throughout the several views.

Referring to the drawings; the mechanism is mounted in the end of the hollow handle bar 1. It consists of an outer fixed 45 sleeve, clamping the spring casing of the control wire and clamped into the end of the said handle bar 1; a rotary sleeve mounted within the fixed sleeve and connected to the hand grip mounted outside of the handle bar 1; and a sliding piece mounted within the rotary piece and engaging slots in 50 both of said sleeves whereby it is prevented from rotation with the rotary sleeve but is given an axial motion therein, said sliding

piece being firmly clamped to the control 55 wire, whereby the sliding motion of said piece is communicated to said wire.

The outer fixed sleeve 2 (Fig. 4) fits snugly within the handle bar 1. It is cylindrical in shape. The outer end is split 60 at 3 and is screw-threaded. A conical screw-threaded plug 4 screws into said outer end and expands it into tight contact with the handle bar 1, thus preventing the mechanism from moving in the said handle and 65 yet allowing its ready removal therefrom when said plug 4 is removed from the sleeve 2. The head of the plug 4 is of substantially 70 the same size as the outer diameter of the handle bar 1. The plug 4 has a central 75 hole therethrough. The inner end 5 of the sleeve 2 is of reduced diameter and is split at 6 and is screw-threaded. A nut 7, having a conical screw-threaded hole therein, screws on said part 5 and forces its parts together 75 whereby the casing 8 of the control wire 9 is firmly clamped to the sleeve 2. The nut 7 is of substantially the size of the outer 80 diameter of the sleeve 2 and fits loosely in the handle bar 1. The sleeve 2 is provided 85 with a long straight slot 10, as clearly shown in Fig. 4.

The rotary sleeve 11 (Fig. 3) is provided with a neck 12 at its outer end, said neck 12 passing through the plug 4 and being provided with a squared portion 13 near its end, said part 13 fitting in a squared hole in the outer plate of the hand grip 14, the extreme end 15 of said neck being screw-threaded to receive a suitable nut 16 outside of said plate, whereby the said hand grip 14 is held in place on the handle bar 1. The hand grip 14 is of the usual form and is shaped to permit a firm grip of the hand. The rotation of the hand grip 14 by the 95 hand, rotates the sleeve 11 through the parts 12 and 13. The main body of the sleeve 11 is hollow and is adapted to receive the sliding piece as hereinafter described. A helical slot 17 is made in said sleeve 11, 100 said slot being in a corresponding position to the slot 10 in the sleeve 2.

The sliding piece 18 fits in the hollow sleeve 11 and is free to move axially therein. It is provided with a central axial hole 105 19 into which the control wire 9 fits. A screw plug 20 enters a suitably prepared hole in the piece 18, at right angles to the axis

thereof, the end of said plug being adapted to engage and bend the wire 9 so that said piece 18 is firmly held to the end of the wire. The screw plug 20 carries two wheels or rollers 21 and 22 thereon which fit in the slots 17 and 10 respectively.

It is evident that, if the sleeve 11 is rotated, the sliding piece 18 will tend to rotate with it and that, since the wheel 22 engages the straight slot 10 in the fixed cylinder 2 and is mounted on the piece 18, the said piece is prevented from thus rotating, hence the only possible movement whereby it may give way to the pressure of the slot 17 (due to the rotation of the part 11) is by sliding in the part 11 to such position that said wheels 21 and 22 may each occupy their positions in said slots 10 and 17, thus the rotary motion imparted to the hand grip 14 is changed to a longitudinal motion of the piece 18 and of the control wire 9.

The mechanism is assembled and installed in the following manner:—

The nut 7 and the sleeve 2 are passed independently over the cover 8 of the wire 9 a sufficient distance so that the wire 9 extends out of said sleeve; then the piece 18 is placed on the end of the wire 9; and then the sleeve 11 is slipped over the piece 18; then the sleeve 2 is drawn back over the sleeve 11, and the screw 20, with its wheels 21 and 22, is inserted through the slots 10 and 17 into the piece 18 until it firmly clamps the wire 9 therein; then the nut 7 is screwed on the part 5 of the sleeve 2 and clamps the cover

8 thereto; then the mechanism is passed into position within the handle bar 1 and the plug 4 is screwed over the neck 12 and into the open end of the sleeve 2 to clamp the mechanism into said position and to prevent its movement therefrom; then the hand grip 14 is passed over the end of the handle bar 1 and is fitted to the squared part 13 of the neck 12; and then the nut 16 is screwed into place to hold the said hand grip in such position.

Having described my invention, what I claim is:

In a device of the class described, the combination with a hollow handle bar; of an outer sleeve fitting within said handle bar and having a straight longitudinal slot therein; means for fixedly clamping the outer end of said sleeve in said handle bar; a control wire within a casing; means for clamping the inner end of said fixed sleeve to said wire casing; a hollow rotary inner sleeve mounted within said outer sleeve and having a central neck extending out from the handle bar, said sleeve having a helical slot therein; a sliding piece having a hole therein adapted to receive the control wire; a screw passing through the slots in said outer and inner sleeves and into said sliding piece to clamp said control wire therein; and a hand grip mounted outside of the handle bar and secured to the neck of said inner rotary sleeve whereby said sleeve may be operated.

RAYMOND P. PACKARD.
